UNITED STATES PATENT OFFICE.

EBEN R. PACKER, OF WILMETTE, ILLINOIS, ASSIGNOR TO Q & C COMPANY, OF NEW YORK, N. Y., A CORPORATION OF MAINE.

PORTRABLE DERAIL.

1,207,788.

Specification of Letters Patent. Patented Dec. 12, 1916.

Application filed September 18, 1915. Serial No. 51,331.

To all whom it may concern:

Be it known that I, EBEN R. PACKER, a citizen of the United States, residing at Wilmette, county of Cook, State of Illinois, have invented a certain new and useful Improvement in Portable Derails, and declare the following to be a full, clear, and exact description of the same, such as will enable others skilled in the art to which it pertains to make and use the same, reference being had to the accompanying drawings, which form a part of this specification.

My invention has for its object to produce a portable derailing device which is applicable to rails of various sizes, may be placed on or removed from a rail quickly and conveniently and, when on a rail, automatically lock itself against creeping in advance of a wheel to be derailed.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a side elevation of a fragment of a railway rail having thereon a derailing device arranged in accordance with my invention; Fig. 2 is a top plan view of the parts shown in Fig. 1; and Fig. 3 is a view looking toward the left from the right hand end of Figs. 1 and 2, the rail being shown in section.

Referring to the drawing, 1 represents a railway rail and 2 a derailing block adapted to derail a wheel passing along the same in one direction that is from the right toward the left in Figs. 1 and 2, and permit a wheel going in the opposite direction to pass freely over the same. On one of the long sides of the block is a long depending flange, 3, having its lower end bent inwardly as indicated at 4 to underlie the corresponding side of the head of a rail to which the block is applied. The flange is made deep enough so as to permit the insertion of any of the standard rail heads between the bottom of the block and the top of the inwardly projecting portion, 4, of the flange. On the under side of the block opposite to the flange 3 and having its mouth directed toward the same is a jaw, 5, in which lies a rotatable locking dog, 6, held in place by a vertical

pin or shaft, 7. The inner end of the locking dog is gradually curved, as indicated at 8, on a radius which increases gradually from the front end, that is the end toward the derailing end of the block toward the rear; the parts being so constructed and arranged that some portion of the cam surface, 8, will engage with the web of any rail on which the block is adapted to be placed and cause the rail to be clamped between the dog and the flange, 3, of the block.

It will be seen that when a wheel engages with the derailing end of the block, that is the right hand end in Figs. 1 and 2, any movement of the block in advance of the wheel would result in a corresponding movement of the pivotal point of the dog while the cam face of the latter remained fulcrumed on the web of the rail. The result would be a swinging of the locking dog and an increase in distance from the web of the rail to the pivotal point of the dog or, in other words, a tightening of the clamping action. A projecting portion of the dog at one side of the jaw, may be provided with a series of holes, 80, through which the shackle of a lock, 9, may be passed so as to prevent the unauthorized removal of the block from the rail. If desired, the block may be provided with an upwardly projecting lug, 10, which may easily be struck with a hammer for the purpose of releasing the locking dog after it is wedged tightly in place through use.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. In combination, a derailing block having on one side a depending flange and on the other side a jaw having its open side directed toward said flange, and a cam-shaped locking dog mounted in said jaw to swing about a vertical axis, a portion of said dog projecting outwardly beyond one side of said jaw and being provided with perforations for receiving the shackle of a padlock.

2. In combination, a derailing block hav-

ing on one side a depending flange and on the other side a jaw having its open side directed toward said flange, and a cam-shaped locking dog mounted in said jaw to swing about a vertical axis, a portion of said dog projecting outwardly beyond one side of said jaw and being provided with

perforations for receiving the shackle of a pad-lock, the dog having at an outer point thereon an upwardly projecting lug.

10

In testimony whereof, I sign this specification.

EBEN R. PACKER.
